UNITED STATES PATENT OFFICE.

CHARLES L. BURDICK, OF KANSAS CITY, MISSOURI.

DESIGN FOR AN AIR-BRUSH CASE.

SPECIFICATION forming part of Design No. 18,329, dated May 22, 1888.

Application filed March 21, 1888. Serial No. 268,027. Term of patent 14 years.

To all whom it may concern:

Be it known that I, CHARLES L. BURDICK, of Kansas City, Jackson county, Missouri, have invented and produced a new and original Design for Cases for Air-Brushes or Air-Pencils, of which the following is a full, clear, and exact description, reference being had to the accompanying drawings, forming a part hereof.

In the drawings, Figure 1 is a perspective view of my new design of case. Fig. 2 is a side elevation of same; and Fig. 3 is a transverse section through the body of the case on line $x x$, Fig. 2.

My design consists in a substantially-cylindrical body, A, of approximately circular or hexagonal shape in cross section, having an enlargement or an angular figure, B, at one end,

and having a projection, C, or an arm projecting from the body portion intermediately of its ends. 20

Having thus described my design, what I claim is—

The design for an air-brush case herein shown and described, consisting of an approximately cylindrical body, an angular enlargement surrounding one end of said body, and a projection located on the body intermediately of its ends. 25

In testimony whereof I affix my signature in presence of two witnesses.

CHAS. L. BURDICK.

Witnesses:

S. S. MOREHOUSE,
J. C. HIGDON.
